R. AVERILL

MIXER

Filed July 31, 1922

FIG. 1

FIG. 2

ROGER AVERILL
INVENTOR.

BY R. W. Smith.
ATTORNEY.

UNITED STATES PATENT OFFICE.

ROGER AVERILL, OF LOS ANGELES, CALIFORNIA.

MIXER.

Application filed July 31, 1922. Serial No. 578,845.

To all whom it may concern:

Be it known that I, ROGER AVERILL, a citizen of the United States, residing at Los Angeles, county of Los Angeles, State of California, have invented new and useful Improvements in Mixers, of which the following is a specification.

This invention relates to trucks employed in concrete work, and has for its object 10 the provision of a truck having a body for the transportation of the dry ingredients of the concrete, from a central supply, where they are loaded in the proper proportion, to the particular work, the 15 truck also including a distinct mixing and conveying apparatus into which the load of dry material is fed when the work has been reached, and a suitable water supply also discharging into the mixing apparatus, for 20 hydration of the dry gravel, sand, cement, and the like, during the movement of the same through the mixing and conveying apparatus, in order that properly mixed wet concrete may be finally discharged from the 25 truck.

The invention will be readily understood from the following description of the accompanying drawings, in which:

Fig. 1 is a side elevation of a truck constructed in accordance with the invention, and shown partly in medial vertical section.

Fig. 2 is a transverse section on the line 2—2 of Fig. 1.

Fig. 3 is a detail plan view of the transmission of the truck.

The improved truck construction includes a usual chassis 1, wheels 2, transmission housed within casing 3, and drive shaft 4, 45 the power of propulsion of the truck being supplied by the usual motor 5.

The body for the truck is supported upon stringers 6 carried by the side frames of the chassis, and the body may be of usual 45 design extending from the cab 7 to the rear of the truck, and adapted to carry a load of loose, dry material, such as sand, gravel, and cement.

The truck body is illustrated as comprising the base 10, and side and end walls 11, with a suitable discharge opening 12 in the front medial portion of the base.

A mixing and conveying mechanism is mounted beneath the truck body, and extends the length thereof, with its front end

in alignment with, and communicating with the interior of the truck body through the opening 12.

The mixing mechanism includes a shell 13 supported from the underside of base 10, and forming an elongated conduit terminating in a discharge spout 14 beyond the rear end of the truck. A shaft 15 is journaled in this conduit, and carries a spiral blade 16, so that when said shaft is rotated, 65 the material fed through opening 12 from the truck body to the shell 13, will be thoroughly mixed and moved along by the spiral conveyor, for discharge at the spout 14.

Means are provided for supplying water 70 to the mixing apparatus, and for this purpose pipes 17 upon the front end wall of the truck body, discharge into opening 12 at opposite sides thereof. The pipes are shown as extending to the top of the truck 75 body, and communicating with a common supply pipe 20, which may be mounted on the outer surface of the front end wall of the body, said pipe being preferably provided with valvular connecting means 21, 80 whereby a hose or the like may be readily connected to said pipe.

The driving connection for rotating the spiral conveyor is preferably actuated by the motor of the truck, said driving connection being inoperative when material is being transported in the truck, and adapted to be engaged, through operation of suitable control mechanism, when the work is reached and after transmission 3 is placed 85 in neutral, or inoperative position with relation to drive shaft 4, in order to actuate the mixing and conveying mechanism, for hydration and discharge of the material in the truck.

The driving connection is shown as comprising an auxiliary transmission having the shaft 22, said auxiliary transmission being mounted in a housing 23 supported by the main transmission housing 3. The 100 auxiliary transmission is driven in any usual manner from the power shaft 30 extending from motor 5 into housing 3, and is provided with a manual control lever 25 for operatively engaging or disengaging the 105 same.

A sprocket 26 is fixed upon shaft 22, in alignment with a sprocket 27 upon the end of shaft 15 extending beyond the truck body, and a sprocket chain 28 is received on said 110

sprockets, so that when shaft 22 is rotated by the motor 5, the spiral conveyor will be driven thereby.

It will be noted that by the use of a truck 5 as thus described, rehandling of the concrete material, as is the present practice, is eliminated. The dry ingredients for the concrete, are mixed and loaded in the truck body in the proper proportion, at the central 10 plant, and the truck then hauls the material to the work. The spiral conveyor and mixer is then set in motion, and the material is shoveled through opening 12 into the same, with the required amount of water 15 being supplied through pipes 17 for hydration of the dry material. The water and material for the concrete are thoroughly mixed in the conveyor mechanism, and the wet concrete is finally discharged through 20 spout 14, ready for use.

While I have illustrated and described the preferred practical embodiment of the device, it will be apparent that various changes may be made in the construction, 25 combination, and arrangement of parts, without departing from the spirit of the invention.

What is claimed is:

1. A motor driven truck, a body mounted on said truck and having a flat bottom spaced slightly above the truck drive mechanism, said bottom having a discharge opening therein at the front end of said body and comprising a relatively small portion of the 30 area of said bottom whereby a load of loose material may be carried on said bottom without movement of the main portion of the load through said opening, a casing mounted beneath the bottom of said body 35 above said drive mechanism and extending 40

the length of said body and communicating at its forward end with the opening in said bottom and forming a discharge at its rear end, a rotatable spiral conveyor and mixer in said casing, a power shaft driven by the 45 truck motor, a power transmission between said shaft and said drive mechanism, and an auxiliary power transmission between said power shaft and said spiral conveyor having means for disengaging the same. 50

2. A motor driven truck, a body mounted on said truck and having a flat bottom spaced slightly above the truck drive mechanism, said bottom having a discharge opening 55 therein at one end of said body and comprising a relatively small portion of the area of said bottom whereby a load of loose material may be carried on said bottom without movement of the main portion of the load through said opening, a casing 60 mounted beneath the bottom of said body above said drive mechanism and extending the length of said body and communicating at one end with the opening in said bottom and forming a discharge at its opposite end, 65 and a rotatable spiral conveyor and mixer in said casing.

3. A motor driven truck, a body mounted on said truck and having its bottom spaced above the truck drive mechanism, said bottom having a discharge opening therein, a casing mounted beneath the bottom of said body above said drive mechanism and communicating at one end with the opening in said bottom and forming a discharge at its 70 opposite end, and conveying and mixing means in said casing.

In testimony whereof I have signed my name to this specification.

ROGER AVERILL.
